DANCING DOLL

José R. Zavala, San Pedro, Calif.

Application September 27, 1949, Serial No. 118,043

3 Claims. (Cl. 46—45)

1

This invention relates to toys, and more particularly to an electrically-operated dancing doll toy.

A main object of the invention is to provide a novel and improved dancing doll toy of the electrically-operated type, said toy being very simple in construction, being attractive in appearance, and providing a combination of rhythmic movement and rhythmic illumination in its action.

A further object of the invention is to provide an improved electromagnetically-operated dancing doll toy device which is inexpensive to manufacture, which is rugged in construction, and which involves a minimum amount of wiring.

Further objects and advantages of the invention will become apparent from the following description and claims, and from the accompanying drawings, wherein:

Figure 1 is a vertical cross-sectional view taken through an electromagnetically-operated dancing doll toy constructed in accordance with the present invention;

Figure 2 is a horizontal cross-sectional view taken on line 2—2 of Figure 1;

Figure 3 is a perspective view illustrating a modified form of the dancing doll toy constructed in accordance with the present invention.

Referring to the drawings, 11 designate a generally-cylindrical hollow base of insulating material, such as plastic or the like, comprising a bottom cover 12 to which is secured a hollow shell member 13. Secured to the central portion of the bottom cover 12 is an upwardly-directed, magnetic core 14 having a central pole 15 and outer poles 16 and 17. Wound on pole 15 is a coil 18, one terminal of coil 18 being connected through a switch 19 to one line wire 20, and the other terminal of coil 18 being connected through a conventional interrupter device 21 to the other line wire 22.

The top wall of shell 13 is dished downwardly to define a large circular recess 23, said recess having an annular upwardly and outwardly-inclined side wall 24. Designated at 25 is a magnetic armature having enlarged end portions 26, 28. Secured to the respective end portions 26, 28 are the respective inclined arcuate leaf springs 27, 27, the outer arcuate edges of the leaf springs engaging the lower portions of the wall 24 at diametrically-opposed positions. As shown in Figure 1, the springs 27, 27 normally support the armature 25 in an elevated position slightly spaced above the bottom wall of the recess 23.

2

Secured to the enlarged end portions 26, 28 are the respective vertical support members 28, 28, and secured to the top ends of said vertical support members is the dancing doll figure 29. Figure 29 is preferably made of translucent material, such as plastic or the like. Connecting the upper end portions of the vertical supports 28, 28 is a horizontal bar element 30, preferably of insulating material, and mounted on the intermediate portion of said bar element is a lamp 31. Wound on armature 25 is a coil 32, the respective terminals of said coil being connected to the respective terminals of the lamp 31 by lead wires shown respectively at 33 and 34.

When the line wires 20 and 22 are connected to a suitable source of current, either alternating current or direct current, and switch 19 is closed, the coil 18 becomes energized, attracting the armature 25 against the tension of the springs 27, 27. This moves the doll 29 downwardly.

When the interrupter device 21 opens the circuit, the coil 18 becomes de-energized, releasing the armature 25 and allowing the springs 27, 27 to raise the armature to its normal elevated position. This moves the doll upwardly. The above operation goes on continuously, causing the doll 29 to be reciprocated at a frequency corresponding to the frequency of operation of the interrupter device 21. The intermittent energization of coil 18 causes a current to be induced in the coil 32, whereby the lamp 31 is energized intermittently, providing an intermittent glow synchronized with the rhythm of reciprocation of the doll 29. Consequently, the doll 29 reciprocates rhythmically and at the same time is intermittently illuminated providing a very entertaining and interesting effect.

In the embodiment of the invention shown in Figure 3, a jointed doll 35 is employed in place of the doll 29 and its associated supporting elements of Figure 1. As shown in Figure 3, the doll 35 has freely-jointed arms 36, 36 and freely-jointed legs 37, 37. The lower portions of the legs 37, 37 are provided with feet 38, 38 of magnetic material which are disposed in the circular recess 23 of the base 11. The body of the doll 35 is supported on a rigid rod 39 secured at its bottom end to a hemispherical, weighted member 40 which rests on the wall of the recess 23. In operation, the magnetic feet 38, 38 are intermittently attracted and released by the magnetic field produced at the poles of the magnetized core 14, said magnetic field being alternately developed and destroyed by the operation of the interrupter device 21 in the same manner

as in the embodiment illustrated in Figures 1 and 2. The jointed doll 35 is consequently rhythmically excited into movement, causing the body of the doll to be oscillated and causing the arms and legs of the doll to be agitated in a rhythmic manner.

While certain specific embodiments of electrically-operated dancing doll toys have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A dancing doll comprising a hollow base, a magnetic core positioned within said base and secured therein, an energizing coil wound about said core and supported thereon, a translucent doll figure positioned above said base, mounting means resiliently supporting said doll figure on said base for movement toward and away from the latter, said mounting means comprising a pair of leaf springs arranged in spaced end to end confronting relation with respect to each other and having their non-confronting ends engaging said base, and a magnetic armature positioned in the space intermediate said leaf springs and supported on the confronting ends of the latter in an elevated position spaced above said base, an inductive pickup coil wound about said armature and supported thereon, and a circuit means electrically connected to said energizing coil, said circuit means comprising means to intermittently energize the latter to thereby effect the movement of said doll figure.

2. A dancing doll comprising a hollow base, a magnetic core positioned within said base and secured therein, an energizing coil wound about said core and supported thereon, a translucent doll figure positioned above said base, mounting means resiliently supporting said doll figure on said base for movement toward and away from the latter, said mounting means comprising a pair of leaf springs arranged in spaced end to end confronting relation with respect to each other and having their non-confronting ends engaging said base, and a magnetic armature positioned

in the space intermediate said leaf springs and supported on the confronting ends of the latter in an elevated position spaced above said base, an inductive pickup coil wound about said armature and supported thereon, light emitting means positioned within said doll figure and electrically connected to said pickup coil, and a circuit means comprising means to intermittently energize said energizing coil to thereby effect the movement of said doll figure and to intermittently energize said light emitting means.

3. A dancing doll comprising an imperforate hollow insulating base, a magnetic core wholly enclosed within said base and secured therein, an energizing coil wound about said core and supported thereon, a translucent doll figure positioned above said base, mounting means including a movable magnetic armature mounted above the base and resiliently supporting said doll figure on said base for movement toward and away from the latter, an inductive pick-up coil wound about said armature and supported thereon, light-emitting means positioned within said doll figure and electrically connected to said pick-up coil, and a circuit electrically connected to said energizing coil, said circuit comprising means to intermittently energize said energizing coil to thereby effect the movement of said doll figure and to intermittently energize said light-emitting means.

JOSE E. ZAVALA.
